Primary Examiner — Austin Murphy(74) *Attorney, Agent, or Firm* — Birch, Stewart, Kolasch & Birch, LLP(57) **CLAIM**

We claim the ornamental design for a hanger for ironing board, as shown and described.

DESCRIPTION

FIG. 1 is a perspective view of a hanger for ironing board showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a partial enlarged view showing a state of use thereof;

FIG. 9 is a partial enlarged view showing another state of use thereof; and,

FIG. 10 is a partial enlarged view showing the other state of use thereof.

Broken lines illustrate environmental condition only and form no part of the claimed design.
